UNITED STATES PATENT OFFICE

BOY F. MUHLENBRUCK, OF HAMPTON, IOWA

PROPELLER MOUNTING

Application filed November 8, 1929. Serial No. 405,717.

The present invention contemplates the provision of a double propeller construction for aeroplanes and the like, which materially increases the efficiency of the motor, the invention being constructed to permit its association with the regular propeller shaft of the machine, or its removal therefrom as the occasion may require.

The nature and advantages of the invention will be better understood when the following detail description is read in connection with the accompanying drawing, the invention residing in the construction, combination and arrangement of parts as claimed.

In the drawing forming part of this application like numerals of reference indicate similar parts in the several views, and wherein:—

Figure 1 is a sectional view through the invention showing it associated with the usual propeller shaft of a machine.

Figure 2 is a sectional view taken on line 2—2 of Figure 1.

Referring to the drawing in detail, 10 indicates the base of the motor and wherein 11 is the usual propeller shaft.

The construction forming the subject matter of the present invention, embodies a sleeve 12 adapted to receive the adjacent ends of 30 the propeller shaft 11, to which it is secured by suitable fastening elements 13, the latter being also utilized to secure the hub 14 of a beveled gear 15 attached to the sleeve 12 as clearly illustrated in Figure 1. Projecting

35 forwardly from the sleeve 12 and in a line with the propeller shaft 11, is a shaft 16 upon which is mounted the hub 17 of a beveled gear 18, and attached to this gear is one of the propellers indicated at 19. The 40 hub 20 of this propeller is arranged between the gear 18 and a disk 21 mounted on the shaft 16, and passed through these parts are suitable bolts for holding the propeller attached to the gear as will be readily understood.

45 Surrounding the propeller shaft 11 in spaced concentric relation thereto, is a ring like member 22 in the nature of a bracket, which includes arms 23 utilized to secure the bracket to the machine 10 through the 50 instrumentality of suitable fastening elements

24. Carried by the ring like member 22 are bearing sockets 24' arranged at diametrically opposite points, each socket having journaled therein the shaft 25 of a beveled gear 26, these latter mentioned gears meshing with 55 the gears 15 and 18 respectively, above referred to. The inner ends of the shaft 25 are also journaled in a bearing ring 27 which is supported upon the sleeve 12.

It will be noted that the outer end of the 60 shaft 16 is slightly tapered as at 28, and mounted upon this tapered extremity is the hub of the other propeller indicated at 29, the propeller being attached to the shaft in any suitable manner. Arranged between the 65 respective propellers is a spacing sleeve or collar 30, one end of which bears against the disk 21 while the opposite end is flanged as at 31 and bears against the hub of the propeller 29. By use of a plurality of propellers arranged one in advance of the other, the efficiency of the motor is materially increased, the forward propeller rotating in an anti-clockwise direction, while the rear propeller operates in a clockwise direction. 70

The construction has been devised to permit of its use in conjunction with aeroplanes or the like in place of the ordinary propeller, and the invention can be easily and quickly attached to the usual propeller shaft in the 80 manner illustrated in the drawing, after the ordinary propeller is removed from the shaft 11.

While it is believed that from the foregoing description the nature and advantages of the 85 invention will be readily understood, I desire to have it known that I do not limit myself to what is herein illustrated and described, and that such changes may be restored to when desired as fall within the scope of what 90 is claimed.

What I claim is:

In combination with a motor and propeller shaft therefor, of an attachment therefor comprising a sleeve receiving said shaft, a 95 shaft projecting forwardly from the sleeve in a line with the propeller shaft, a gear carried by said sleeve, a second gear carried by the shaft of said sleeve, a propeller carried by the second mentioned gear, an additional pro- 100

steller carried by the shaft of the sleeve and arranged in advance of the first mentioned propeller, a ring like member surrounding the sleeve in spaced concentric relation thereto, and arranged immediately adjacent the motor brackets carried by the ring like member for securing the same to the motor base, and a plurality of pinion gears journaled in said ring like member and meshing with the aforementioned gears for the purpose specified.

In testimony whereof I affix my signature.
ROY F. MUHLENBRUCK.
